UNITED STATES PATENT OFFICE

2,599,453

CAM GRINDING MACHINE

Russell P. Hock and Clarence J. Green, Worcester,
Mass., assignors to Norton Company, Worcester,
Mass., a corporation of Massachusetts

Application May 5, 1950, Serial No. 160,344

5 Claims. (Cl. 51—101)

1

The invention relates to grinding machines, and more particularly to a rock bar actuating mechanism for a cam grinding machine.

One object of the invention is to provide a simple and thoroughly practical actuating mechanism for the rock bar of a cam grinding machine. Another object is to provide a hydraulically operated rock bar actuating mechanism for controlling movement of the rock bar during a grinding operation and also movement of the rock bar to and from an operative position. Another object is to provide a hydraulically operated rock bar actuating mechanism whereby a reduced pressure may be maintained between the master cam and the follower roller over the nose of the cam and whereby a substantially uniform pressure may be maintained between the master cam and the follower roller on the rise and fall of the cam. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of the improved cam grinding machine;

Fig. 2 is a horizontal sectional view, on an enlarged scale, taken approximately on the line 2—2 of Fig. 1;

Fig. 3 is a plan view, on an enlarged scale, of the work head with the cover removed;

Fig. 4 is a cross-sectional view, taken approximately on the line 4—4 of Fig. 3;

Fig. 5 is a fragmentary sectional view, on an enlarged scale, of a portion of the rock bar actuating cylinder showing the relative position of the ports and piston lands;

Fig. 6 is a cross-sectional view, on an enlarged scale, taken approximately on the line 6—6 of Fig. 5, through the cylinder and piston;

Fig. 7 is a longitudinal sectional view, on an enlarged scale, through the accumulator; and

Fig. 8 is a combined hydraulic and electric diagram of the control mechanism for actuation of the rock bar.

A cam grinding machine has been illustrated in the drawings having a base 10 which supports a longitudinally traversable work table 11. The table 11 serves as a support for a pivotally mounted rock bar 12. The rock bar 12 is pro-

2

vided with a rotatable master cam spindle 13 which is supported in a pair of spaced bearings 14 and 15 (Fig. 2) which are fixedly supported on the rock bar 12. The master cam spindle 13 is supported within a work head frame 16. The master cam spindle 13 is provided with a work center 17 to support the left-hand end of a cam shaft to be ground. The rock bar 12 also serves as a support for a footstock 18 having a work supporting center 19 which is arranged to support the right-hand end of a cam shaft to be ground. The master cam spindle 13 supports one or more master cams 20 in operative relationship with a rotatable follower roller 21 which is 15 slidably keyed to a rotatable shaft 22. If more than one master cam 20 is provided, an indexing mechanism is provided for indexing the master cam roller longitudinally on the shaft 22 in a manner well known in the prior art. This mechanism may comprise a star wheel 23 which is actuated by a dog bar (not shown) on the base 10. The star wheel 23 is connected through a rack and gear mechanism 24 to index the master cam roller longitudinally in timed relation with 20 the positioning movement of the work table 11. This mechanism is substantially identical with that shown in the expired U. S. Patent No. 1,783,755 to C. G. Trefethen et al., dated December 2, 1930, to which reference may be had for 25 details of disclosure not contained herein.

A suitable driving mechanism is provided for positively rotating the master cam spindle 13 during the rocking movement of the rock bar 12. This mechanism may comprise an electric motor 25 mounted on top of the work head frame 16. The motor 25 is provided with a motor shaft 26 having a multiple V-groove pulley 27 which is connected by multiple V-belts 28 with a multiple V-groove pulley 29 supported on an idler shaft 30. The shaft 30 is supported on the work head frame 16. A multiple V-groove pulley 31 is formed integral with the pulley 29 and is connected by multiple V-belts 32 with a multiple V-groove pulley 33 journaled on anti-friction 35 bearings 34 which are in turn supported by a hollow bracket 35 which is fastened to the work head frame 16. The pulley 33 is connected by a universal joint 36 with a shaft 37. The other end of the shaft 37 is connected by a universal joint 38 with the master cam spindle 13. It will be readily apparent from the foregoing disclosure that rotation of the motor shaft 26 will be imparted through the driving mechanism above described to rotate the master cam spindle 13. Rotation of the master cam spindle 13 and the mas-

ter cam 20 in engagement with the master cam roller 21 will impart a rocking or oscillating movement to the rock bar 12 so as to grind a predetermined contour on the cam being ground.

The base 10 also serves as a support for a transversely movable wheel slide 40 which is slidably supported on the usual and well known V and flat ways (not shown) formed on the upper surface of the base 10. The wheel slide 40 rotatably supports a wheel spindle (not shown) which is provided at its left-hand end with a grinding wheel 41. A driving mechanism is provided for the grinding wheel 41 comprising an electric motor 42 mounted on the upper surface of the wheel slide 40. The motor 42 is connected by means of a belt drive (not shown) contained within a belt guard 43 to rotate the wheel spindle and grinding wheel 41. A manually operable feed wheel 44 is rotatably supported on the front of the machine base by means of which the wheel slide 40 may be adjusted toward and from the work supporting table 11. A manually operable table traverse wheel 45 is also provided for traversing the work table 11 longitudinally relative to the base 10 to facilitate positioning the cam to be ground into operative relation with the grinding wheel 41.

A hydraulically operated mechanism is provided for actuating the rock bar 12 so as to maintain the master cam 20 in operative engagement with the follower roller 21. It is desirable that the pressure between the master cam 20 and the follower roller 21 be substantially uniform during rotation of the master cam 20 in order that a cam may be ground to the desired and predetermined contour. A fluid pressure mechanism is provided comprising a cylinder 50 having a piston 51 slidably mounted therein. The piston 51 is provided with a pair of spaced piston lands 52 and 53 which may be formed integral with a double-end piston rod 54. The piston rod 54 is pivotally connected by means of a stud 55 with a link 56. The link 56 is pivotally connected by means of a stud 57 with an arm 58 which is adjustably fixed to the rock bar 12. In order to facilitate adjustment of the arm 58 relative to the rock bar 12, the arm 58 is spaced from the rock bar 12 by means of a rocker roller 59. A pair of spaced clamping screws 60 and 61 pass through clearance holes in the arm 58 and are screw threaded into the rock bar 12. It will be readily apparent from the foregoing disclosure that by manipulation of the screws 60 and 61, the arm 58 may be rocked relative to the rock bar so as to adjust the position of the arm as desired.

A reservoir 62 is provided within the base of the machine. Fluid is pumped from the reservoir 62 through a pipe 63 by means of a fluid pump 64 which forces fluid under pressure through a pipe 65. A pressure reducing and regulating valve 66 is connected to the pipe 65. A pipe 67 is connected to the upper end of the regulator valve 66 to pass fluid under the desired pressure through a check valve 68 and through a pipe 69 to a control valve 70.

The control valve 70 is preferably a piston type valve comprising a valve stem 71 having a plurality of spaced valve pistons 72, 73 and 74 formed integrally therewith. The valve pistons 72, 73 and 74 form a pair of spaced valve chambers 75 and 76. A compression spring 77 serves normally to urge the valve stem 71 in a direction toward the right (Fig. 8) to maintain the valve stem 71 in its right-hand end position. An electric solenoid 78 is operatively connected to

the valve stem 71 so that when energized the solenoid 78 serves to shift the valve stem 71 toward the left into its left-hand end position as illustrated in Fig. 8. Fluid under pressure passing through the pipe 69 enters the valve chamber 76 and passes through a pipe 79 into a cylinder chamber 80 to cause the piston 51 together with the piston rod 54 to move toward the left (Fig. 8) so as to rock the arm 58 and rock bar 12 in a counterclockwise direction (Fig. 4) to move the master cam roller 20 into operative engagement with the follower roller 21 for a grinding operation. A pipe 81 connects with the pipe 79 and is provided at its other end with a fluid accumulator 82 which will be more fully described hereinafter.

During movement of the piston 51 toward the left, fluid within a cylinder chamber 83 may exhaust through a port 84 and also through a port 85 to exhaust fluid through a pair of pipes 86 and 87 respectively. The pipe 86 when the port 84 is open passes fluid directly into the valve chamber 75 and through a passage 90, through a pipe 91, through a ball check valve 92 and a pipe 93 into the reservoir. At the same time fluid may exhaust through the pipe 87, through a throttle valve 88 into the pipe 86. A ball check valve 89 is provided to by-pass fluid around the throttle valve 88 when the fluid is moved in the opposite direction. When both of the ports 84 and 85 are open, substantially unrestricted exhaust of fluid from the cylinder chamber 83 may be obtained. As the piston land 52 moves toward the left from the extreme right-hand end position 52a (Fig. 4) fluid may exhaust through both of the ports 84 and 85. The piston land 52 covers the port 85 while still allowing fluid to exhaust through the port 84. As the port 84 is completely covered during movement of the piston land 52 toward the left (Fig. 5), the port 85 is again gradually opened so that fluid may still exhaust from the cylinder chamber 83 through the throttle valve 88 which controls the rate of exhaust therefrom. This staggered arrangement of the ports together with the throttle valve 88 serves to slow down the movement of the rock bar 12 to an operative position just before the master cam 20 goes into engagement with the follower roller 21.

The accumulator 82 may be of the type manufactured by Greer Hydraulics, Inc., Brooklyn, N. Y., and covered by U. S. Patent No. 2,342,356 to J. Mercier, dated February 22, 1944. The accumulator 82 comprises a metallic shell or casing within which is mounted a flexible bladder 95. A valve 96 is provided at the upper end of the accumulator whereby air under pressure may be supplied to the bladder 95. The lower end of the bladder is provided with a metal collar or seat 97 which is arranged to seat upon a surface 98 fastened to the lower end of the accumulator 82. The bladder 95 may be made of rubber or synthetic rubber and is preferably loaded to about 50 lbs. per sq. in. pressure. It will be readily apparent that when fluid under pressure from the pump 64 is passed through the pipe 79 into the cylinder chamber 80, the piston 51 together with the piston rod 54 will be moved toward the left (Figs. 4 and 8) to rock the rock bar 12 to an operative position with the master cam 20 in operative engagement with the master cam roller 21. As the master cam shaft 13 rotates during a grinding operation, the rock bar 12 will be caused to oscillate in accordance with the shape of the master cam 20. As the rock bar is

moved in a clockwise direction by rotation of the master cam 20 in engagement with the follower roller 21, the piston rod 54 and the piston 51 will be moved toward the right (Figs. 4 and 8). Fluid cannot pass back through the pipe 69 since the check valve 63 prevents back-flow of fluid therethrough. As the piston 51 moves toward the right, fluid within the cylinder chamber 80 is forced out through the pipe 79 through the pipe 81 into the accumulator chamber 99 thereby displacing the bladder 95 by compressing the air within the bladder 95. The operating pressure within the cylinder chamber 80 may be 100 lbs. per sq. in. for maintaining the master cam 20 at the desired operative contact with the follower roller 21. This pressure may be varied as desired by regulation of the valve 66. The actual applied load between the master cam 20 and the roller 21, in this case, will be approximately 100 lbs. at the top of the arm 58. As the nose of the master cam 20 rides over the roller 21, the pressure increases slightly due to the pressure built up within the accumulator 82 so that the pressure between the master cam 20 and the follower roller 21 is approximately 150 lbs. per sq. in. If desired this pressure may be further reduced by decreasing the effective area of the piston 51 so that a smaller volume of fluid is required for maintaining the desired pressure between the master cam and the follower roller 21. With a lesser volume of fluid required, a lesser volume of fluid is displaced from the chamber 80 during normal operation, therefore, the increase in pressure over the nose of the cam will be similarly decreased.

The piston land 52 is provided with a plurality of perforations 52a which are arranged parallel to the axis of the valve stem 54 so that fluid within the cylinder chamber 83 is free to pass therethrough into the chamber 83a formed between the piston lands 52 and 53.

As a further explanation of the action of the piston 51, as the rock bar 12 rocks in a counter-clockwise direction (Fig. 4) so that the master cam 20 approaches the master cam roller 21, the piston land 52 closes off the port 84. Since the ports 84 and 85 are not in line, there is an overlap so that up to the point of closing off the port 84 fluid within the chambers 83 and 83a is free to exhaust through both of the ports 84 and 85. When port 84 is closed off fluid can still pass from the chamber 83 through the perforations 52a and out through the port 85, through the needle valve 83 to the control valve 70. This action serves to cushion the rapid movement of the rock bar 12 in a counter-clockwise direction just before the master cam 20 moves into engagement with the roller 21. This cushioning action takes place only while the port 84 is closed, but it serves to check the speed of movement of the piston 51 sufficiently to give a soft action of the movement of the master cam 20 into engagement with the follower roller 21.

During the normal rocking movement of the rock bar 12 as caused by the master cam 20, both the port 84 and the port 85 are located between the piston lands 52 and 53.

After a cam has been ground to a predetermined size and contour, it is desirable to rock the rock bar in a clockwise direction so that the arm 58 is moved to position 58a and the piston lands 52 and 53 are moved to broken-line positions 52a and 53a (Fig. 4). It is desirable to automatically control the movement of the rock bar 12 to an inoperative position so that the cam being ground

is allowed to remain in contact with the grinding wheel for a predetermined number of rotations of the cam being ground. This is preferably accomplished by means of an electric counter which are old and well known in the art, such as for example, the Microflex electric counter manufactured by the Signal Electric Corporation of Moline, Illinois. As illustrated in Fig. 8 an electric counter 104 is provided. The rock bar 12 is provided with a projecting arm 100 which is arranged during the normal rocking movement of the rock bar 12 to engage an actuating roller 101 on an actuating arm 102 of a normally closed limit switch 103. Each time the rock bar 12 oscillates during the grinding operation, the arm 100 opens the limit switch 103 to impart an impulse to the counter 104. After a predetermined number of impulses, a circuit is opened to deenergize the solenoid 78 thereby releasing the compression of the spring 77 which shifts the valve stem 71 toward the right (Fig. 8) to shift the valve pistons 72, 73 and 74 into the reverse position. When the valve 70 is in the reverse position, fluid under pressure within the pipe 69 passes through the valve chamber 75 and through the pipe 86 and the pipe 87, through the ports 84 and 85 respectively into the chamber 83 to cause the piston 51 to move toward the right thereby rocking the rock bar 12 in a clockwise direction to an inoperative position with the master cam 20 separated from the follower roller 21. During movement of the piston 51 toward the right, the piston land 52 first closes off the port 84 and then as the port 84 opens momentarily closes off the port 85. At no time are either of these ports completely closed so that fluid under pressure is continuously passed into either the chamber 83a, through the perforations 52a into the cylinder chamber 83 or passed directly into the cylinder chamber 83 to provide a rapid movement of the piston 51 toward the right to an inoperative position.

The operation of this improved cam grinding apparatus will be readily apparent from the foregoing disclosure. A normally operable switch 105 is closed to start a grinding operation. The closing of the switch 105 serves to energize the solenoid 78 so that the control valve 70 is shifted into the position illustrated in Fig. 8 thereby admitting fluid through the pipe 79 into the cylinder chamber 80 to move the rock bar 12 in a counter-clockwise direction so as to move the master cam 20 into operative engagement with the follower roller 21. The electric motors 25 and 42 are started to start the rotation of the master cam spindle 13 and the rotation of the grinding wheel 41. Rotation of the master cam spindle 13 and the master cam 20 serves to oscillate the rock bar 12 so as to generate a predetermined contour on a cam being ground. During the grinding operation fluid under pressure within the cylinder chamber 80 serves to maintain the master cam 20 in engagement with the follower roller 21 at a predetermined pressure. As the master cam rotates up the left of the cam, the piston 51 moves toward the right so that fluid in the chamber 80 is displaced into the accumulator chamber 99. During the movement of the piston 51 toward the right, the check valve 91 is closed and a partial vacuum formed within the cylinder chamber 83 which assists the pressure within the cylinder chamber 80 in maintaining the master cam 20 in operative engagement with the follower roller 21. During each actuation of the rock bar 12 by rotation of the master cam, the limit switch

103 is opened to impart an impulse to the counter 104. After a predetermined number of impulses, the counter breaks a circuit that deenergizes the solenoid 78 thereby shifting the control valve 70 into a reverse position to cause the rock bar to move to an inoperative position thereby separating the master cam 20 from the roller 21.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a cam grinding machine having a pivotally mounted rock bar, a rotatable master cam spindle thereon, a master cam on said spindle, a rotatable master cam follower roller, means to rotate said spindle, and a rock bar actuating mechanism comprising a piston and cylinder operatively connected to move the rock bar to and from an operative position and to maintain the master cam in operative engagement with the follower roller with the desired operating pressure during rotation of the master cam, a control valve to control the admission to and exhaust of fluid from said cylinder, and a fluid accumulator operatively connected to said cylinder to facilitate displacement of fluid from the cylinder caused by the rocking movement of said rock bar due to rotation of the master cam during a grinding operation so as to maintain the master cam in operative engagement with the follower roller with the desired pressure.

2. In a cam grinding machine, as claimed in claim 1, in combination with the parts and features therein specified of a pair of offset exhaust ports in said cylinder to control the exhaust of fluid therefrom when the rock bar is moved to an operative position, both of said ports serving initially to facilitate substantially unrestricted exhaust of fluid from said cylinder, and an adjustable throttle valve to regulate fluid exhausting from the one of said ports, said piston having a land which closes the second port prior to engagement of the master cam with the follower roller to cushion engagement therebetween.

3. In a cam grinding machine, as claimed in claim 1, in combination with the parts and features therein specified in which the piston is formed with two spaced lands, a pair of offset exhaust ports in said cylinder to control the exhaust of fluid therefrom when the rock bar is moved to an operative position, both of said ports serving initially to facilitate a substantially un-

restricted exhaust of fluid from said cylinder, and an adjustable throttle valve to regulate fluid exhausting from one of said ports when one of the piston lands closes the other port prior to engagement of the master cam with the follower roller to cushion engagement therebetween, said piston lands being arranged so that both of the exhaust ports remain open during the normal oscillation of the rock bar during grinding.

4. In a cam grinding machine, as claimed in claim 1, in combination with the parts and features therein specified of a solenoid to actuate said control valve, a switch to energize said solenoid to shift the control valve to admit fluid under pressure to the rock bar cylinder to cause the rock bar to move to an operative position with the master cam in engagement with the follower roller, an electric counter, and a switch actuated by each normal rocking movement of the rock bar during a grinding operation to actuate said counter, said counter serving after a predetermined number of oscillations of the rock bar to deenergize said solenoid so as to shift the control valve into a reverse position to shift the rock bar to an inoperative position.

5. In a cam grinding machine having a pivotally mounted rock bar, a rotatable master cam spindle thereon, a master cam on said spindle, a rotatable master cam roller, means to rotate said spindle and a rock bar actuating mechanism comprising a piston and cylinder operatively connected to move the rock bar to and from an operative position and to maintain the master cam in operative engagement with the follower roller with the desired operating pressure during rotation of the master cam, a control valve to control the admission to and exhaust of fluid from said cylinder, means including a pressure regulating valve to supply fluid under pressure to said control valve, a check valve to maintain fluid pressure on the pressure side of the piston during grinding to maintain the master cam in engagement with the follower roller, and a fluid accumulator operatively connected to the pressure end of said cylinder which serves to facilitate displacement of fluid from said cylinder caused by the rocking movement of the rock bar due to rotation of the master cam during grinding.
